PRESSUREPROOF COMBUSTION CHAMBER

Walter Gustav Noack, Baden, Switzerland, assignor to Aktiengesellschaft Brown Boveri & Cie., Baden, Switzerland, a joint-stock company of Switzerland

Application August 20, 1931, Serial No. 558,261,
and in Germany September 1, 1930

12 Claims. (Cl. 122—24)

This invention relates to pressure-proof combustion chamber for subjecting combustible gases to combustion under high pressure, such as used in connection with gas turbines or steam generators, and it has among its objects simplified construction of such combustion chambers and reduction of their weight and costs.

The objects of the invention will be best understood from the following description of exemplifications thereof, reference being had to the accompanying drawings wherein

Fig. 1 is a diagrammatic view of a steam generator with a combustion chamber made in accordance with the invention;

Figs. 2 and 3 are horizontal and vertical sectional views, respectively, of a section of the combustion chamber of Fig. 1;

Figs. 4 and 5 are horizontal sectional views of combustion chambers embodying modifications of the invention;

Fig. 6 is a vertical sectional view of the chamber section of Fig. 5;

Fig. 7 is a horizontal sectional view of a combustion chamber structure embodying a modification of the invention;

Fig. 8 is a vertical sectional view of a chamber section embodying a further form of the invention; and

Fig. 9 is a vertical sectional view of a combustion chamber structure embodying a modification of the invention.

In my copending application Serial No. 343,745, filed March 1, 1929, I have disclosed a novel type of steam generator in which an extremely high rate of steam generation is secured by periodically subjecting a combustible mixture to explosion-type combustion in a pressure-proof chamber and utilizing the high pressure of the hot combustion gases formed in the chamber for imparting to said gases a very high velocity through a set of gas tubes traversed on the outside by a steam generating fluid, such as water, thereby securing a very high rate of heat transference from the hot gases to the water and, as a consequence, very large steam generation within a relatively small structure.

The combustion chamber of such steam generator must be able to withstand the high pressure of the combustion gases, and it must be able to do it while it is exposed to the high temperature of such gases. To meet this double strain, of the pressure and of the heat, the walls of the combustion chamber must be cooled, and this is ordinarily done by passing the steam generating fluid, such as water, through cooling jackets sur-

rounding the chamber walls, the water taking up the heat from the walls and converting it into steam, which is applied for the production of power. The cooling medium is then subjected to the full steam pressure, which may be considerably higher than the pressure in the combustion chamber. The cooling jacket must thus be able to withstand a higher pressure than the interior of the combustion chamber, and the diameter of the cooling jacket will be considerably greater than the diameter of the chamber which is itself of considerable dimensions. Both conditions entail the provision of very thick walls for the combustion chamber and the cooling jacket, that is, heavy and costly bodies.

Since the heat must be led away through the walls of the chamber, it must traverse the full wall thickness. There is accordingly a great temperature gradient in the wall and large internal strains appear in the wall material. Additional strains develop due to the large thermal expansion of the hot chamber walls relatively to the surrounding cool jacket walls giving further serious design difficulties.

Similar conditions exist also in gas turbines where the combustion gases for driving the turbine blades are generated at high pressure in a pressure-proof combustion chamber and must be cooled to a lower temperature that will not burn the blades before discharge into the turbine. The chamber is therefore likewise ordinarily cooled by a jacket carrying water that takes up the heat and generates steam which is suitably utilized. The chamber as well as the jacket must both withstand high pressures, and their walls must be thick, giving, likewise, heavy and costly structures.

In my prior application Serial No. 343,745, referred to above, I have shown that a much superior water-cooled high pressure combustion chamber may be obtained, by eliminating the water jacket around the chamber, and, instead, mounting a set of water tubes on the inner side of the pressure-resisting walls of the combustion chamber and in this way protecting the wall of the chamber from excessive heating. As the tubes are of relatively small diameter, their wall thickness is small even for high pressures of the cooling liquid. Since the cooling tubes lie on the inner side of the wall, the wall is protected against radiation from the combustion gases. The wall is only heated by the cooled gases collecting between the tubes and the wall, and by contact with the cooling tubes. The temperature of the walls cannot, therefore, be higher than the temperature on the rear side of

the tubes. The temperature is accordingly low, and uniform within the wall, and there is substantially no flow of heat through the walls. The excessive stresses in the chamber walls due to the 5 temperature differences between the outer and inner sides of the chamber walls and the jacket wall are thus eliminated. The only strain imposed on the chamber walls is that of the pressure of the gases in the chamber. The weight 10 of the improved water-cooled pressure-proof combustion chamber is thus considerably smaller and their construction much simpler than in case of chambers having an external jacket.

The present invention provides a further improvement in the construction of pressure-proof combustion chambers with interior tubular wall cooling. In accordance with the present invention the interior wall of the combustion chamber is itself formed by the tubes through which the 20 high pressure cooling medium flows, the tubes being welded together to constitute a smooth inner wall, and in some cases the welds between the tubes are made gas and pressure tight so as to hold the gas in the interior of the chamber 25 without additional outer walls.

In Fig. 1 the invention is shown as applied to the combustion chamber of a steam generator of the type disclosed in my above referred to application Serial No. 343,745, Figs. 2 and 3 being 30 detailed sectional views of the combustion chamber. The steam generator comprises a pressure-proof combustion chamber having a main cylindrical section 2 with an inlet header 3 enclosing the bottom and an outlet header 4 enclosing the 35 top of the chamber. Within the walls of the inlet header 3 is formed a water inlet chamber 5 and within the walls of the outlet header 4 is formed a water outlet chamber 6. A set of water tubes 7 is mounted along the periphery of the chamber 1 forming the inner walls thereof, the tubes being surrounded by a cylindrical outer wall 8, having at its ends flanges 9 within which the ends of the water tubes 7 are secured, as by welding. The tubes 7 are connected between the 40 water inlet chamber 5 and the water outlet chamber 6 to pass water that is heated and vaporized while passing through the tubes, the mixture of hot water and admixed steam being discharged through a conduit 10 into a steam separator 11. The steam separates and collects in the upper 45 part of the separator from where it is supplied to the load, and the water is collected in the lower part of the separator, fresh feed water being supplied thereto through pipe 12. The 50 water from the separator 11 is circulated through water tubes 7 by means of water pump 13 which is connected by pipes 14 between the separator 11 and inlet 15 of water chamber 5.

A combustible mixture, such as a gas or air with 60 fuel admixed thereto, is compressed by compressor 20 and periodically delivered to combustion chamber 1 through conduit 21 and suitably operated inlet valve 22. The admitted compressed combustible charge is subjected to explosive combustion in the chamber, for instance by ignition with spark plugs mounted on the interior wall of the chamber. The resulting high pressure is utilized to drive the hot combustion gases at a velocity of about 200 meters per second or above through a set of gas pipes 26 connected to the upper end of the chamber and leading through the interior of the water tubes 7, the gases being discharged into the gas outlet duct, and therefrom, through pipe 28 into a gas turbine where a part of the energy still remaining 75

in the gases is applied to drive compressor 20 and thus serves to initially compress the combustible charge supplied to the chamber. Additional driving power may be supplied to the compressor by an auxiliary motor 30, such as a Diesel engine, coupled to the gas turbine 29, the total power supplied by the motor and the turbine being proportioned to be sufficient to produce in the compressor the pressure head necessary for imparting to the combustion gases the high velocity and for driving the auxiliary gas turbine to supply a part or all of the initial charging pressure. This charging and explosion process is periodically repeated resulting in a continuous efficient generation of steam.

As pointed out before, the combustion chamber must be able to withstand the high pressure developed by the explosive combustion of the compressed charge while it is exposed to the high temperature of the gases. This is achieved in a way much superior to the prior practices. As seen in detail in Figs. 2 and 3, the main section of the combustion chamber is made by arranging the water tubes 7, which circulate the water that is to be heated and converted into steam, axially 100 parallel close together to form the wall enclosing the interior of the chamber. The adjacent water tubes 7 are either directly welded to each other, or preferably have the interior grooves between each other filled by insertions 31 in the 105 form of a round wire, or of a special form 32 conforming to the outer surfaces of the adjacent tubes as shown in Fig. 4, the insertions being welded to the adjacent tube walls. The welding of the tubes to each other forms tight joints 110 between the tubes and produces a tight enclosure. It is important to have the internal cylindrical surface of the chamber smooth and without interstices so as to prevent trapping of 115 remnant burned or burning gases that might prematurely ignite the next fresh charge. To this end the interstices and junctions between the inner tube sides and insertions are filled during the welding with filler material 33 and the welds then ground with an emery wheel, so that the 120 interior of the chamber wall shall have the character of a continuous unitary wall.

In combustion chambers with water tubes arranged parallel to the chamber axis as shown in Figs. 2 and 3, the tubes are preferably surrounded by the cylindrical wall 8, of steel or similar material. In such constructions, the water tubes 7, before being welded to each other at their inner sides, are tacked, by welding, to the wall 8, at several places, as indicated in Fig. 125 2 at 34, to insure their bearing against the wall. The outer cylinder wall 7 takes up the longitudinal strain exercised by the bottom and top headers 3 and 4 on the main chamber section 2, and also the tangential forces acting in the 130 direction of the circumference of the chamber section 2, although a part of the tangential pressure may be taken up by the welding of the tubes. Since the water tubes 7 lie directly on the inner side of the cylindrical wall 8, the 135 temperature of the wall cannot be higher than the temperature on the rear sides of the water tubes 7. The heat stresses to which combustion chambers with external jackets cooled by a fluid under pressure are exposed, are thus eliminated. The resulting reduction of the heat stresses, and 140 improved distribution of the inner stresses, combined with the relatively small wall thickness required by the small diameter tubes to withstand the high internal steam pressure, enable thus 145 150

construction of a combustion chamber that is much lighter than ordinary high pressure, high temperature combustion chambers, eliminating also the complicated construction problems arising due to the pressure and heat stresses in the chamber walls.

Instead of cylindrical water tubes 7, tubes of special cross section may be used for the chamber wall. Such arrangement is shown in Figs. 5 10 and 6, where the distance between the tubes is increased, and their number decreased by pressing the water tubes 36 throughout their length to an oval shape. Each tube occupies a larger part of the chamber periphery, and the adjacent tubes 15 are welded to each other and joined to form a continuous smooth inner wall by welding and depositing a welding filler at the junctions. The tubes retain their cylindrical shape only at their ends 37 inside the flanges 9, to facilitate their 20 mounting. The water tubes for the chamber wall may also be of trapezoidal form 38, as shown in Fig. 7, to facilitate the building up of the cylindrical chamber walls, the cross section of the tubes being well rounded or beveled at 25 the corners to provide junction spaces for receiving sufficient quantities of welding material.

Pressure-, and temperature-proof combustion chambers for steam generators and gas turbines in accordance with the present invention may also 30 be made by helically wound tubes, as shown in Fig. 8. The individual turns 40 of the water tubes lie one above the other, forming a cylindrical chamber, and the inner sides of the junctions of adjacent tubes are welded to each other and filled 35 with welding inserts 41 and welding metal 42 to provide a smooth interior surface like in the construction shown in Figs. 2 and 3. The end turns of the water tubes 40 are tightly welded to the flanges 44 to which the bottom and top headers 40 3 and 4 are clamped. Water for absorbing the heat of the chamber gases is circulated under pressure through tubes 40, the water being admitted and led away by suitable ducts 49 joined to the ends of the coiled tubes. The tangential 45 forces in the circumference of the chamber produced by the internal pressure in the chamber are taken up by the tubes 40 themselves, and no external cylindrical wall is needed. The welding of the tube turns provides tight joints, and gives 50 a tight pressure-proof chamber. The longitudinal stresses in the chamber wall, impressed by the bottom and top headers 3 and 4 of the chamber, are taken up by tension bolts 45 which also serve to bolt the bottom and top headers to the 55 main cylindrical section formed by the tubes 40. A lagging 47 is provided around the chamber to maintain the bolts at approximately the same temperature as the tubes. The bolts may also be provided with longitudinal bores, as indicated by 60 dotted lines 48, or surrounded by enclosures through which a fluid of the same temperature as in the water tubes 7 is conveyed.

Combustion chambers formed of parallel longitudinally arranged water tubes as described in 65 Figs. 2 and 3 may also be made like the chamber of Fig. 8 without an outer cylindrical wall 7, in which case, however, there must be provided in addition to bolts 45 for taking up longitudinal stresses, also several outer clamping rings surrounding the tubes and taking up the tangential stresses produced by the internal pressure in the chamber.

Instead of using cylindrical helically wound tubes for forming the combustion chamber in Fig. 75 8, tubes of special profile, such as the rectangular

tubes shown in Fig. 9, may be employed, welded at the junctions like the tubes of Fig. 7.

The present application is directed only to the features of my invention disclosed herein involving a pressure resisting combustion chamber, the walls of which are made of adjacently disposed tube elements held together in tight and pressure proof condition. The steam generator apparatus disclosed above in connection with the exemplification of the foregoing invention embodies many other novel features for causing high temperature compressed combustion gases to discharge at a high velocity over a small evaporator structure and generate steam at a high rate as described and claimed in my copending applications, Serial No. 333,453 filed January 18, 1929, Serial No. 343,745 filed March 1, 1929, Serial No. 343,746 filed March 1, 1929, Serial No. 375,138 filed July 1, 1929, Serial No. 414,428 filed December 16, 1929, Serial No. 419,026 filed January 7, 1930, and Serial No. 558,260 filed August 20, 1931.

Having now particularly described and ascertained the nature of my said invention and in what manner the same is to be performed, I declare that what I claim is:—

1. A pressure-resisting combustion chamber for steam generators or gas turbines, comprising a chamber wall formed of adjacently disposed metallic tube elements, closure members joined to said tube wall and constituting therewith a combustion chamber, means for admitting a combustible charge into said chamber and subjecting said charge to combustion under great internal pressure substantially higher than the external pressure, and ducts connected to the opposite ends of said tube elements for passing therethrough a cooling fluid absorbing heat from the hot combustion gases and maintaining within said tube elements a pressure substantially higher than the external pressure, the tube elements forming said chamber wall being welded to each other along their inner junction surfaces and being held together to maintain with said closure members said chamber in pressure-proof condition.

2. A pressure-resisting combustion chamber for steam generators or gas turbines, comprising a tubular chamber wall formed of adjacently disposed metallic tube elements, closure members joined to the opposite ends of said tubular chamber wall and constituting therewith a combustion chamber, means for admitting a combustible charge into said chamber and subjecting said charge to combustion under great internal pressure substantially higher than the external pressure, and ducts connected to the opposite ends of said tube elements for passing therethrough a cooling fluid absorbing heat from the hot combustion gases and maintaining within said tube elements a pressure substantially higher than the external pressure, the tube elements forming said chamber wall being welded to each other along their inner junction surfaces and being held together to maintain with said closure members said chamber in pressure-proof condition.

3. A pressure-resisting combustion chamber for steam generators or gas turbines, comprising a tubular chamber wall formed of adjacently disposed metallic tube elements, closure members joined to the opposite ends of said tubular chamber wall and constituting therewith a combustion chamber, means for admitting a combustible charge into said chamber and subjecting said charge to combustion under great internal pressure substantially higher than the external pressure, ducts connected to the opposite ends of said

- 5 tube elements for passing therethrough a cooling fluid absorbing heat from the hot combustion gases and maintaining within said tube elements a pressure substantially higher than the 86
5 external pressure, the tube elements forming said chamber wall being welded to each other along their inner junction surfaces and being held together to maintain with said closure members said chamber in pressure-proof condition, 86
10 and additional means extending longitudinally along said tubular chamber wall to take up the longitudinal wall stresses imposed by the pressure within said chamber. 86
- 15 4. A pressure-resisting combustion chamber for steam generators or gas turbines, comprising a tubular chamber wall formed of adjacently disposed metallic tube elements, closure members joined to the opposite ends of said tubular chamber wall and constituting therewith a combustion chamber, means for admitting a combustible charge into said chamber and subjecting said charge to combustion under great internal pressure substantially higher than the external pressure, and ducts connected to the opposite ends 90
20 of said tube elements for passing therethrough a cooling fluid absorbing heat from the hot combustion gases and maintaining within said tube elements a pressure substantially higher than the external pressure, the tube elements forming said 95
25 chamber wall being welded to each other along their inner junction surfaces to form a smooth interior chamber surface and being held together to maintain with said closure members said chamber in tight and pressure-proof condition. 100
- 30 5. A pressure-resisting combustion chamber for steam generators or gas turbines, comprising a tubular chamber wall formed of adjacently disposed metallic tube elements, closure members joined to the opposite ends of said tubular chamber wall and constituting therewith a combustion chamber, means for admitting a combustible charge into said chamber and subjecting said charge to combustion under great internal pressure substantially higher than the external pressure, and ducts connected to the opposite ends 105
35 of said tube elements for passing therethrough a cooling fluid absorbing heat from the hot combustion gases and maintaining within said tube elements a pressure substantially higher than the external pressure, the tube elements forming said 110
40 chamber wall being welded to each other along their inner junction surfaces to form a smooth interior chamber surface and being held together to maintain with said closure members said chamber in tight and pressure-proof condition. 115
- 45 6. A pressure-resisting combustion chamber for steam generators or gas turbines, comprising a tubular chamber wall formed of adjacently disposed metallic tube elements, closure members joined to the opposite ends of said tubular chamber wall and constituting therewith a combustion chamber, means for admitting a combustible charge into said chamber and subjecting said charge to combustion under great internal pressure substantially higher than the external pressure, and ducts connected to the opposite ends 120
50 of said tube elements for passing therethrough a cooling fluid absorbing heat from the hot combustion gases and maintaining within said tube elements a higher pressure than the pressure inside said chamber, the tube elements forming said chamber wall being welded to each other along their inner junction surfaces to form a smooth interior chamber surface and being held together to maintain with said closure members said chamber in tight and pressure-proof condition. 125
- 55 7. A pressure-resisting combustion chamber for steam generators or gas turbines, comprising a tubular chamber wall formed of adjacently disposed metallic tube elements, closure members joined to the opposite ends of said tubular chamber wall and constituting therewith a combustion chamber, means for admitting a combustible charge into said chamber and subjecting said charge to combustion under great internal pressure substantially higher than the external pressure, and ducts connected to the opposite ends 130
60 of said tube elements for passing therethrough a cooling fluid absorbing heat from the hot combustion gases and maintaining within said tube elements a pressure substantially higher than the external pressure, the tube elements forming said chamber wall being welded to each other along their inner junction surfaces and having the 135
65 grooves between said junction surfaces filled with metal inserts welded to said surfaces to form a smooth interior chamber surface and being held together to maintain with said closure members said chamber in tight and pressure-proof condition. 140
- 70 7. A pressure-resisting combustion chamber for steam generators or gas turbines, comprising a tubular chamber wall formed of adjacently disposed metallic tube elements, closure members joined to the opposite ends of said tubular chamber wall and constituting therewith a combustion chamber, means for admitting a combustible charge into said chamber and subjecting said charge to combustion under great internal pressure substantially higher than the external pressure, and ducts connected to the opposite ends 145
75 of said tube elements for passing therethrough a cooling fluid absorbing heat from the hot combustion gases and maintaining within said tube elements a pressure substantially higher than the external pressure, the tube elements forming said chamber wall being welded to each other along their inner junction surfaces and having the 150

gitudinal and tangential wall stresses imposed by the pressure within said chamber.

10. A pressure-resisting combustion chamber for steam generators or gas turbines, comprising a tubular chamber wall formed of metallic tube elements helically wound adjacent to each other, closure members joined to the opposite ends of said tubular chamber wall and constituting therewith a combustion chamber, and means connected to the ends of said tube elements for passing therethrough a cooling fluid absorbing heat from the hot combustion gases and maintaining within said tube elements a pressure substantially higher than the external pressure, the tube elements forming said chamber wall being welded to each other along their inner junction surfaces and being held together to maintain with said closure members said chamber in tight and pressure-proof condition, and tension bolts extending longitudinally along said tubular chamber wall to take up the longitudinal wall stresses imposed by the pressure within said chamber.
